UNITED STATES PATENT OFFICE.

CALEB E. SUMMERS, OF DAYTON, OHIO, ASSIGNOR TO GENERAL MOTORS RESEARCH CORPORATION, OF DAYTON, OHIO, A CORPORATION OF DELAWARE.

ENGINE-FUEL VAPORIZER.

Application filed May 22, 1923. Serial No. 640,806.

This invention relates to internal combustion engines and has among its objects to volatilize the fuel which condenses while passing from the carburetor to the engine in 5 take.

Further objects and advantages of the present invention will be apparent from the following description, reference being had to the accompanying drawing wherein a preferred embodiment of the present invention is 10 clearly shown.

The figure of the drawing is a sectional view showing a form of the present invention.

15 In the drawing, a carburetor 20 is connected by a pipe 21 and the neck 22 of a vaporizer 23 with the engine intake manifold 24. Pipe 21 is provided with holes 25 leading into the vaporizer 23.

20 A separate heating chamber surrounding the exterior of the vaporizer 23, which is provided with heat conducting fins 26, is provided by a jacket 27 having an intake 28 adapted to be connected with the engine exhaust manifold, and an outlet 29 for connection with a muffler. Jacket 27 is attached to vaporizer 23 by screws 30, and to pipe 21 by 25 screws 31.

The vaporizer provides a relatively sharp 30 annular portion or baffle 32 for diverting the condensed liquid fuel, which creeps upwardly along the interior surface of pipe 21 during the operation of the engine, into the vaporizer 23. Here, the fuel will be vaporized due 35 to heat transmitted by the fins 26 and walls of the vaporizer from the heating chamber 27. The vaporized fuel will enter the pipe 21 through the holes 25 due to engine suction, and will pass with the fuel stream from pipe 40 21 to the engine intake.

The velocity of the flow of fuel through the pipe 21, caused by the engine suction, builds up a pressure at the opening of the vaporizing chamber, due to the baffle 32, greater than the 45

pressure at the openings 25. This difference in pressure causes the diverted portion of the stream to reverse its movement and to flow through the vaporizer where it is returned

to the stream or column of fuel through the 50 openings 25.

While the form of embodiment of the invention as described constitutes a preferred form, it is to be understood that other forms might be adopted, all coming within the 55 scope of the claims which follow.

What I claim is as follows:

1. In a device of the class described and in combination with a conduit through which a fuel mixture may flow to an internal combustion engine, a heating chamber; a vaporizing chamber arranged between said conduit and said heating chamber whereby the outer wall only of said chamber is heated, and the upper end of which vaporizing chamber is in permanently open communication 60 with said conduit; and means located adjacent the upper end of and extending into said vaporizing chamber for deflecting a portion thereof from the periphery of the stream of fuel mixture flowing along said conduit into 65 said vaporizing chamber; said conduit having holes in its wall whereby and through 70 which the lower end of said vaporizing chamber is placed in communication with the interior of said conduit.

2. In a device of the class described and in combination with a conduit through which a fuel mixture may flow to an internal combustion engine, a vaporizing chamber surrounding said conduit; and a heating chamber surrounding said vaporizing chamber; said conduit having an opening adjacent and leading into the upper end of said vaporizing chamber, and another opening through which the lower end of said vaporizing chamber is placed in communication with the interior of said conduit; and a baffle plate extending into said conduit adjacent said first mentioned opening to thereby deflect a part of the fuel mixture from the periphery of the 90 stream of fuel mixture flowing through said conduit into said vaporizing chamber.

3. In a device of the class described and in combination with a conduit through which a fuel mixture may flow to an internal combustion engine, a vaporizing chamber sur-

rounding said conduit; a heating chamber surrounding said vaporizing chamber; an annular passage adjacent and leading into the end of said vaporizing chamber the nearer the engine; an annular baffle plate arranged adjacent said passage and extending into said conduit to thereby deflect fuel mixture from the periphery of the stream flowing through

and a series of openings located adjacent the other end of said vaporizing chamber and whereby the interior thereof is placed in communication with the interior of said conduit.

In testimony whereof I hereto affix my signature.

CALEB E. SUMMERS.
